PIPE LINE FILTER

Frank J. Morgan, Houston, Tex.

Application April 9, 1943, Serial No. 482,436

3 Claims. (Cl. 210—165)

This invention relates to new and useful improvements in filters or strainers for pipe lines, the principal object being to provide means for straining oil or water in pipe lines and affording means for readily collecting the sediment accumulated thereby.

Another important object of the invention is to provide a structure of the character stated which will save considerable time and labor in its operation.

Other important objects and advantages of the invention will become apparent to the reader of the following description.

In the drawings:

Figure 1 represents a side elevational view of the structure.

Figure 2 is a vertical sectional view on the line 2—2 of Figure 1.

Figure 3 is a section on the line 3—3 of Figure 1.

Figure 4 is a side elevational view of the strainer.

Figure 5 is a fragmentary detailed sectional view through the box and drawer.

Figure 6 is a fragmentary side elevational view of the valve.

Referring to the drawings wherein like numerals designate like parts, it can be seen that numeral 5 denotes a valve body having an inlet 6 and an outlet 7. A partition 8 in the lower portion of the body 5 is constructed to provide a valve seat 9.

The lower portion of the body 5 is flanged and a box 10 for receiving a slide drawer 11 is also flanged and secured to the flanges at the lower portion of the body 5 by bolts 12.

Numeral 13 denotes a bonnet which is secured by screws 14 to the top of the body 5 and on this is secured a packing gland 14 through which a threaded stem 15 is feedable. The stem 15 has a tapered valve 16 at its lower end for engagement with the seat 9 and a hand wheel 17 at its upper outer end.

Numeral 18 denotes a substantially semi-cylindrical screen having a laterally disposed flange 19 at its upper and lower ends, the lower flange resting on the partition 8, while the upper flange 19 is interposed between the bonnet 13 and the upper end of the body 5. The screen 18 is disposed in spaced concentric relation to the body 5 at the outlet side of the latter and the open side of the screen 18 faces the inlet 6 so that any sediment or foreign matter collected on the inside of the strainer will precipitate to the partition 8 and will drop through the opening 9 at 55

the valve seat into the drawer 11. The upper portion of the valve head 16 contacts the inner surface of strainer 18 to scrape the sediment from said surface when said valve is moved longitudinally of the filter body.

It can be seen that one side of the box 10 has a removable plate 20 secured in place by machine screws or the like 21.

A by-pass pipe 22 extends from the box 10 upwardly to the bonnet 13 and has a valve 23 therein.

When taking out the tray, first close valve 16, then open the by-pass valve 23 until pressure in box 10 is relieved, and then close valve 23. After turning off valve 23 remove tray 11. After replacing the tray, open the by-pass valve 23 for opening the valve 16 to avoid sudden building up of pressure in box 10, and then close valve 23.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A pipe line filter comprising a body having a vertically elongated tubular chamber and provided with inlet and outlet openings respectively at opposite sides of said chamber, a substantially semi-tubular open-ended strainer mounted longitudinally of and within said chamber in spaced relation to the longitudinal wall of the latter and with its open side facing the inlet, said body being open at the top and having a bottom wall provided with a central opening, an outwardly projecting flange on the bottom end of said strainer resting on said bottom wall and fitting in the chamber, a valve head movable longitudinally of the chamber within the strainer and movable downwardly to close said central opening, a hollow bonnet secured on the upper end of the body, an outwardly projecting flange on the upper end of the strainer clamped between the upper end of the body and the bonnet, an open-top box secured to the lower end of the body and having a removable side closure plate, and a removable tray in said box.

2. A pipe line filter comprising a body having a vertically elongated tubular chamber and provided with inlet and outlet openings respectively at opposite sides of said chamber, a substantially semi-tubular open-ended strainer mounted longitudinally of and within said chamber in spaced relation to the longitudinal wall of the latter

and with its open side facing the inlet, said body being open at the top and having a bottom wall provided with a central opening, an outwardly projecting flange on the bottom end of said strainer resting on said bottom wall and fitting in the chamber, a valve head movable longitudinally of the chamber within the strainer and movable downwardly to close said central opening, a hollow bonnet secured on the upper end of the body, an outwardly projecting flange on the upper end of the strainer clamped between the upper end of the body and the bonnet, an open top box secured to the lower end of the body and having a removable side closure plate, a removable tray in said box, a by-pass pipe affording communication between the box and the bonnet, and a shut-off valve in said by-pass pipe.

3. A pipe line filter comprising a body having a vertically elongated tubular chamber and provided with inlet and outlet openings respectively at opposite sides of said chamber, a substantially

semi-tubular open-ended strainer mounted longitudinally of and within said chamber in spaced relation to the longitudinal wall of the latter and with its open side facing the inlet, said body being open at the top and having a bottom wall provided with a central opening, an outwardly projecting flange on the bottom end of said strainer resting on said bottom wall and fitting in the chamber, a valve head movable longitudinally of the chamber within the strainer and movable downwardly to close said central opening, a hollow bonnet secured on the upper end of the body, an outwardly projecting flange on the upper end of the strainer clamped between the upper end of the body and the bonnet, an open top box secured to the lower end of the body and having a removable side closure plate, and a removable tray in said box, the upper end of said valve head contacting the inner surface of said strainer.

FRANK J. MORGAN.
